UNITED STATES PATENT OFFICE.

THOMAS G. RAKESTRAW, OF DETROIT, MICHIGAN, ASSIGNOR TO RICHARD O. BRAN-
DENBURG AND RALPH S. MOORE, BOTH OF DETROIT, MICHIGAN.

STEAM TRAP.

Application filed February 27, 1922. Serial No. 539,400.

To all whom it may concern:

Be it known that I, THOMAS G. RAKESTRAW, a citizen of the United States, residing at Detroit, in the county of Wayne and State of Michigan, have invented a new and useful Steam Trap, of which the following is a specification.

This invention relates to water circulating traps such as are employed in connection with steam power systems.

The general object of the invention is to provide a device of this character which will automatically function to collect the water of condensation from a steam circulating line and deliver such water back to the boiler, and the particular object of the present invention is to simplify and reduce the number of parts commonly required and to generally improve the construction and enhance the efficiency in operation of that type of trap employing tiltable twin tanks for alternatively controlling the admission and discharge of the steam and water.

In attaining these objects the invention contemplates the elimination of the usual independent valve sets and fittings for the respective tanks, by combining and embodying in a unitary or single valve structure means affording a pivotal support for the tiltable tanks, and also for establishing a common control for the admission and discharge of steam and water alternately to and from said tanks respectively, whereby the number of fittings, working joints and packings usually required are materially reduced and liability to disarrangement of parts and leakage is correspondingly lessened.

A preferred embodiment of the invention is illustrated in the accompanying drawings, in which,

Fig. 1 is a central transverse vertical sectional view of the device.

Fig. 2 is a longitudinal view taken on dashed line 2—2 of Fig. 1.

Fig. 3 is a transverse vertical section on dashed line 3—3 of Fig. 2.

Fig. 4 is a longitudinal vertical sectional view on dashed line 4—4 of Fig. 1.

Referring to the parts of the device as shown on the drawings, 1 indicates a rectangular supporting base having spaced upright brackets 2 at opposite ends respectively, and

fixedly secured to extend at opposite ends 55 respectively through said brackets is a hollow elongated cylindrical valve body 3 having a centrally enlarged cylindrical portion 4 forming a valve chamber therein. Said chamber is divided into separate upper and 60 lower water and steam compartments 5, 6, 7 and 8, respectively, by an off-center vertical partition 9 intersected by a central horizontal partition 10, which latter partition extends to the closed end walls of the valve 65 body 3 and divides the interior thereof into separate upper and lower water and steam passages 5', 6', 7' and 8' respectively communicating with corresponding compartments of said valve chamber. 70

The peripheral wall of the compartment 5 is provided with oppositely disposed bridged water ports 5^a, and the outer end of the passage 5' is connected through the valve body 3 with a water inlet pipe 11 leading to a suitable source of supply, usually the water of condensation from a steam circulating system (not shown), and the compartment 6 is similarly provided with water ports 6^a through which and the passage 6' 80 water is admitted to a delivery pipe 12 connected to the corresponding end of said valve body and adapted to extend to a steam boiler (not shown) or other point of delivery. The upper steam compartment 7 85 is provided in alignment with the ports 5^a with opposed ports 7^a, which communicate through the passage 7' with a vent or exhaust pipe 13 connected to the corresponding end of the valve body and opening to the atmosphere, and the lower steam compartment 8 has opposed ports 8^a slightly staggered out of alignment with the ports 6^a for controlling the delivery of live steam through the passage 8' from a steam pipe 95 14, which is connected therewith through the end of the valve body and extends to a steam boiler (not shown) or other source of steam pressure. (See Fig. 4).

Embracing the end portions of the valve 100 body between the uprights 2 and the valve chamber are bearing bushings 15, and rotatively embracing said valve chamber and the adjacent ends of said bushings, to oscillate thereon, is a valve casing 16 formed with a removable end closure 16' and having each end provided with a stuffing-box bearing 17 for establishing close working con-

nections to prevent leakage between said ends and the valve body. Said casing is lined interiorly with a bearing sleeve 18, and inserted in parallel recesses in the periphery of the valve chamber upon opposite sides of the ports therein are packing strips 19 which yieldably engage the inner face of said sleeve to prevent leakage between said ports, and there is also a packing ring 20 inserted in a peripheral groove in line with the partition 9 to prevent leakage between the steam and water compartments of said chamber. (See Figs. 1 and 2).

Formed through the sleeve 18 and wall of the valve casing are diametrically opposite ports 21 adapted to register alternatively with the ports 5^a and 6^a upon respective sides of the water compartments 5 and 6 of the valve chamber. Said ports 21 communicate respectively through oppositely extending passages 22 formed jointly in opposed integral extensions 23 of the valve case connected with up-turned pipe elbows 24 and upon which twin cylindrical tanks 25 are respectively mounted through the bottom by like pipe nipples 26 for the admission of water to and from said tanks and valve upon oscillatory movement of said valve casing. Ports 27 are also oppositely formed in the valve casing to communicate alternatively with the ports 7^a and 8^a upon respective sides of the steam compartments 7 and 8, and said ports 27 are each connected at corresponding sides of the valve case with a corresponding tank 25 by a pipe extension 28 having a coupling connection 29 with the top of said tank for the alternate admission of live stream thereto and the exhaust of air and used stream therefrom. (See Figs. 1 and 3).

Mounted upon each side of the base 1, in line with the corresponding elbow extension 24 of the valve casing, is an upright dash-pot comprising a cylinder 30 containing a hollow piston 31 ported for the admission of oil from said cylinder, and which is normally yieldably stressed outwardly of the cylinder by a coiled spring 32 interposed between said piston and cylinder. The pistons of said dash-pots are adapted to engage said extensions to check and limit the oscillatory movement of said valve casing, and the tension of the springs is such as to impart thereto a partial return movement to effect the automatic closing of certain of the steam ports, as will be hereinafter described.

It will now be understood that in the operation of the trap the two tanks are alternatively filled with water, and the water is alternatively forced out of the tanks through the admission alternatively thereto of steam under pressure, and that the admission and discharge of both the steam and water are automatically controlled in common through the actuation of the unitary

valve structure by the oscillation of the tanks. The operations in the oscillations of the tanks, and the control of the ports of the valve are such that when one tank is filling with water the opposite tank is caused to discharge as follows:

When the valve casing is in the position shown in Fig. 1, water admitted by the feed pipe 11 to the passage 5' and compartment 5 of the valve chamber will flow through the registering ports 5^a and 21, and through the passage 22 and pipe connection 26 into the corresponding tank 25, and while said tank is filling the contents of the other tank will be caused to discharge through its pipe connection 26, passage 22, the registering ports 21 and 6^a of the compartment 6 of the valve chamber and through the passage 6' and delivery pipe 12 to the boiler or other point of delivery. In this described position of the water controlling ports the steam ports of the valve will be positioned as shown in Fig. 3, in which steam under pressure in the supply pipe 14, passage 8' and compartment 8 will have been admitted through the registering ports 8^a and 27, and through the pipe connections 28-29 into the top of the tank discharging for setting up pressure therein to force such discharge, while the tank filling with water will be vented and relieved of any accumulated air or steam pressure which may discharge back through the inlet pipe connections 28-29 of said tank, and out through the registering ports 27 and 7^a of the compartment 7 of the valve chamber and through the passage 7' and exhaust pipe 13 to the atmosphere.

When the filling tank shall have accumulated sufficient weight to overbalance the discharging tank, it will swing downwardly engaging the extension 24 of the valve case with the piston of the corresponding dash-pot, which under the force of the impact will recede in checking the rotative movement of the valve case through which the ports will be shifted to establish communication with the corresponding tank in opposite order to that described. As the weight of the tank upon the piston of the dash-pot is lessened by the discharge of the water and the spring urging said piston outwardly overcomes the load of the emptying tank, said piston will impart a sufficient reverse rotative movement to the valve casing as will effect the closing of the ports 8^a and 27 to cut off the steam pressure to the discharging tank and prevent the loss of steam through the water passages following the emptying of said tank. It will be noted that the slight movement of the valve case necessary to close the port 8^a, which is so positioned as to partly cover the port 27 when the other registering steam and water ports of the valve are in full open position, will not be sufficient to cut off the established

communication through such ports which will continue to function in partially closed positions.

The requirement for the installation of traps of this character in steam circulating systems is well understood by those familiar with the art, and will not require description further than to state that it is essential to position the trap at such an elevation to 10 the boiler to be served as will insure the delivery of the water thereto by gravity under balanced pressure with that of the boiler.

What I claim is:

1. A steam trap comprising a base, a hollow elongated valve body fixedly mounted on said base and having a plurality of separated passages therein, a valve casing journaled to oscillate on said valve body and having ports registrable with certain of said 15 passages in oscillated positions of said casing, a pair of tanks mounted directly on said casing to oscillate the same and having passages controlled in common by said ports to communicate therethrough with certain 20 of the passages of said valve body in limiting positions of oscillation of said casing, and cushioning means limiting the oscillating movement of said casing and reacting to 25 impart reverse movement thereto to effect the closing of certain of said ports and passages.

2. A steam trap comprising a pair of tanks having inlet and outlet passages, a unitary oscillatory valve structure mounting said tanks and having ports controlling communication with said passages in common through oscillatory movement imparted by said tanks, and a spring pressed plunger yieldably engageable with said 40 valve structure to limit movement thereof and reacting to impart movement thereto for closing certain of said ports.

3. A steam trap comprising a stationary elongated hollow valve body having a plurality of divided passages communicating with a centrally enlarged cylindrical chamber, said chamber having opposed pairs of

ports communicating with respective passages, a valve casing embracing said cylindrical chamber and journaled to oscillate 50 on said valve body, said casing having opposed pairs of ports registrable alternatively with corresponding opposite ports of the respective passages of said body and having opposed hollow extensions forming passages 55 for the corresponding ports of said casing, a tank mounted on each extension in communication with the passage thereof, and a pipe extension from each of said tanks communicating with opposite ports of said casing and corresponding passages of said valve body for establishing circulation through 60 said tanks and passages alternatively with oscillations of said casing.

4. A steam trap comprising a stationary 65 elongated hollow valve body having a plurality of divided passages communicating with a centrally enlarged cylindrical chamber, said chamber having opposed pairs of ports communicating with respective passages, a valve casing embracing said cylindrical chamber and journaled to oscillate on 70 said valve body, said casing having opposed pairs of ports registrable alternatively with corresponding opposite ports of the 75 respective passages of said body and having opposed hollow extensions forming passages for the corresponding ports of said casing, a tank mounted on each extension in communication with the passage 80 thereof, a pipe extension from each of said tanks communicating with opposite ports of said casing and corresponding passages of said valve body for establishing circulation through said tanks and 85 passages alternatively with oscillations of said casing, and yieldable means limiting oscillatory movement of said casing and reactive to impart movement thereto to cut off circulation through certain of said 90 passages.

In testimony whereof, I sign this specification.

THOMAS G. RAKESTRAW.
